UNITED STATES PATENT OFFICE.

CHARLES W. HIGBY, OF JACKSON, MICHIGAN.

CORSET-WAIST.

SPECIFICATION forming part of Letters Patent No. 397,801, dated February 12, 1889.

Application filed October 19, 1888. Serial No. 288,654. (No model.)

To all whom it may concern:

Be it known that I, CHARLES W. HIGBY, of Jackson, in the county of Jackson and State of Michigan, have invented a certain new and useful Improvement in Corsets, of which I declare the following to be a full, clear, and exact description, reference being had to the accompanying drawings, forming part of this specification.

10 This invention has for its object an improvement in corset-waists; and the invention consists in a corset-waist constructed and with its parts combined and arranged in the manner hereinafter with particularity shown, described, and claimed.

15 In the accompanying sheet of drawings, Figure 1 is a front view of my corset; Fig. 2, a view of one of the halves of the corset spread out. Figs. 3 to 9 are detail views of the various pieces which compose one half or side of the corset.

Similar letters of reference indicate like parts in the several views.

20 This invention, while it applies equally well in the construction of corsets of any kind, applies particularly to what are known as "corset-waists," or to corsets somewhat lighter and adapted to fit more closely to the human form, but without the stiffness and rigidity 30 of the heavier and ordinary corset, as it is understood.

The invention pertains especially, therefore, to the construction of corset-waists, so that while the waists afford a certain amount 35 of support they do not interfere with the comfort of the wearer, nor do they impair the wearer's health. To accomplish these ends, and at the same time construct a corset-waist that shall be comparatively inexpensive, I 40 make my waist in the ordinary two parts, A and B, each of said parts being the counterpart of the other so far as the general form and construction are concerned, each of the parts A and B being made from the usual 45 corset-waist material—such as sateen or any other suitable fabric—and each half of the waist may be provided with the ordinary corset-steel and metal fastenings at the front, as in Fig. 1; or buttons and button-holes may be 50 used for uniting the front edges of the corset-waist, and the backs of the sections A and

B are provided with the ordinary eyelets and lacing-strings. So far my corset-waist does not differ from other waists; but the first or bust section, 1, is formed practically straight 55 and parallel with the bust-steel *a*, and it is stitched to the front of the waist in which the steel is inserted and to section 2, so that it may have a certain fullness. The section 2 referred to has one straight or vertical edge, 60 which is joined to section 1, and its other edge is of the scroll shape shown in Fig. 4, and in this section 2 are inserted cords *b*, which extend from the top edge of the corset-waist diagonally toward the front of the corset, the 65 section 2 extending in like manner from the top to the bottom of the corset-waist, but being in part cut out and curved, so that its curved cut-away portion, in connection with a similar cut-away part of section 1, will admit of the insertion of the breast-pocket or bust-piece *c*. Stitched to section 2 of my waist is section 3, the front edge of which is of scroll form and stitched to section 2, and its rear or back edge forms nearly a straight but diagonal line. This section 3 extends practically 70 from the top to the bottom edges of the corset, and to it are fixed suitable cordings, *d*, these cordings extending from the top to the bottom of the corset and diagonally toward 75 the front of the waist. To the section 3 is stitched section 4. This section at its front edge corresponds in shape to the back edge of section 3, before described; but its rear or back edge is practically straight, so that the 80 general shape of section 4 is that of a right-angled triangle. To this section 4 is fixed a series of cords, *e*, which extend diagonally across half the width of the section and toward the back of the waist, as in Fig. 2. To 85 section 4 is sewed the last or back section, 5. This section 5 is provided with a series of cords, *f*, and the ordinary eyelets for lacing, and in these particulars the back section, 5, does not materially differ from similar sections in corsets; but the upper part of section 90 95 5 is shaped as in Fig. 5, and to it is secured a shoulder-strap, *C*. Between the front of the corset in which the steel *a* is inserted, as before stated, and the curved and cut-away parts 100 of sections 1 and 2 is inserted the pocket or bust-piece *c*, this bust-piece being stitched

to the sections 1 and 2 and also to a yoke, D, and it is stitched to this yoke D with plaits or "gathers" *g* to give requisite fullness to the bust-piece. To the yoke D, by means of 5 a button, buckle, or other contrivance, are attached the free ends of the shoulder-strap C, and in general terms this completes the construction of one half of my corset-waist, which construction is substantially duplicated in the 10 other half, as before stated.

The advantages arising from the foregoing construction are found primarily in the lightness due to the form and arrangement of its several sections and cordings, which afford 15 sufficient support and stiffness to the wearer, while at the same time admitting of a close and perfect fit, and besides the gathering of the bust-piece *c* to the yoke D affords a fullness to the bust-pieces that would not otherwise be attained when these pieces are united 20 to a yoke, and the yoke itself is an important feature, for it adds a firmness and support to the bust-pieces which they would not otherwise have. The firmness and support of the 25 bust-pieces or pockets *c* are materially increased by the shoulder-straps C, which, extending, as before described, pass over the shoulder of the wearer, and by so doing not only sustaining the entire corset-waist, but 30 particularly holding up through the yokes D the bust-pieces *c*.

By reason of the button or buckle which attaches the shoulder-strap to the yoke the degree of support in this way obtained may 35 be in this way increased or diminished, and, as is obvious, instead of the cords *b*, *d*, *e*, and *f* bones or other suitable material may be employed.

Having now described my invention, what I 40 claim as new, and desire to secure by Letters Patent, is—

1. A corset-waist each side or half thereof having in combination a front section extending from the top to the bottom of the waist, provided with fastenings, the oblong yoke D, 45 attached at one end to the front section and extending across the upper side of the breast-piece, the sections 1 and 2, the former having its lateral edges substantially straight and parallel to each other and the concave upper 50 edge, and the latter having the concave edge extending from a point near the middle of one side of the section to its top and the scroll-shaped edge at the other side, and the breast-piece *c*, with the convex lower edge, the breast-piece being inserted between the concave edges of the sections 1 and 2 and the yoke and stitched to said sections and yoke, substantially as and for the purpose described. 55

2. A corset-waist each side or half thereof having in combination a front section provided with fastenings, the oblong yoke D, extending across the upper side of the breast-piece, sections 1, 2, 3, 4, and 5, and the breast-piece *c*, with the convex lower edge, sections 3 65 and 5, extending from the top to the bottom of the waist, and sections 1 and 4 from the bottom part way to the top of the waist, section 1 having the concave upper edge and section 2 the concave edge extending from a point 70 near the middle of one side of the section to its top, the breast-piece being inserted between the concave edges of the sections 1 and 2 and the yoke and stitched to said sections and yoke, substantially as and for the purpose described. 75

CHARLES W. HIGBY.

In presence of—

W. J. REYNOLDS,
H. E. CHAPIN.
